US00D914729S

(12) **United States Design Patent** (10) Patent No.: **US D914,729 S**
(45) Date of Patent: **** Mar. 30, 2021**

(54) **DISPLAY SCREEN OR PORTION THEREOF
WITH GRAPHICAL USER INTERFACE**

- (71) Applicant: **Apple Inc.**, Cupertino, CA (US)
- (72) Inventors: **Scott Balles**, Brooklyn, NY (US); **Gary Butcher**, San Jose, CA (US); **Imran Chaudhri**, San Francisco, CA (US); **Jonathan P. Ive**, San Francisco, CA (US); **Ernest Rowe**, San Jose, CA (US); **Alessandro Francesco Sabatelli**, San Francisco, CA (US); **Eric Lance Wilson**, San Jose, CA (US)
- (73) Assignee: **Apple Inc.**, Cupertino, CA (US)
- (**) Term: **15 Years**
- (21) Appl. No.: **29/730,548**
- (22) Filed: **Apr. 6, 2020**

CLAIM

The ornamental design for a display screen or portion thereof with graphical user interface, as shown and described.

DESCRIPTION

FIG. 1 is a front view of a display screen or portion thereof with graphical user interface showing the claimed design; FIG. 2 is a second embodiment thereof; FIG. 3 is a third embodiment thereof; FIG. 4 is a fourth embodiment thereof; FIG. 5 is a fifth embodiment thereof; FIG. 6 is a sixth embodiment thereof; FIG. 7 is a seventh embodiment thereof; FIG. 8 is an eighth embodiment thereof; FIG. 9 is a ninth embodiment thereof; and, FIG. 10 is a tenth embodiment thereof.

The broken lines in the figures show a display screen or portion thereof and form no part of the claimed design.

1 Claim, 2 Drawing Sheets

Related U.S. Application Data

a continuation of application No. 29/538,921, filed on Sep. 9, 2015, now Pat. No. Des. 762,701, which is a continuation of application No. 29/457,353, filed on Jun. 9, 2013, now Pat. No. Des. 738,889.
